UNITED STATES PATENT OFFICE

CLAUDE M. PAXSON, OF TIPTON, OKLAHOMA

AUTOMOBILE SPEEDOMETER

Application filed April 17, 1931. Serial No. 530,931.

This invention relates to motor vehicle speedometers and more particularly to illumination therefor and has for the primary object, the provision of an illuminating means so arranged that the speed indicating numbers or characters may be effectively illuminated so that they may be more easily read by the occupants of the vehicle from either seat of said vehicle and also whereby the season and trip indicating numbers may be more easily read.

Another object of this invention is the provision of stenciling the numbers in the speed indicating drum and arranging within the drum an illuminating means whereby the light rays of said means will effectively actuate the numbers to render them more easily read without undue glare to the eyes of the observer.

20 A further object of this invention is the provision of a novel mounting for the illuminating means, whereby the latter may be easily accessible for repairs and which supports said illuminating means for illuminating all of the members of the speedometer.

With these and other objects in view, this invention consists in certain novel features of construction, combination and arrangement of parts to be hereinafter more fully described and claimed.

For a complete understanding of my invention, reference is to be had to the following description and accompanying drawings, in which

25 Figure 1 is a front elevation illustrating a speedometer constructed in accordance with my invention.

Figure 2 is a sectional view illustrating the same.

30 Figure 3 is a top plan view illustrating the illuminating means mounted on the casing of the speedometer.

Figure 4 is a sectional view taken on the line 4-4 of Figure 3.

35 Figure 5 is a sectional view illustrating the slots in the speed indicating drum for permitting the light rays to extend into the casing of the speedometer for the purpose of illuminating the season and trip numbers and taken on the line 5-5 of Figure 4.

Referring in detail to the drawings, the numeral 1 indicates a conventional type of speedometer including a casing 2, a drive means 3, and an arbor 4 mounted within the casing and carrying the total and trip numbers 5 and 6 readable through the usual slots in the dial face 7. The dial face 7 is protected by the usual transparent panel 8. The arbor 4 also carries the speed indicating drum 9 driven from the operating means 3 in the usual manner. The drum 9 has the speed indicating numbers 10 stenciled thereon and said drum is held in operative position with the driving means 11 by brackets 12 detachably secured to the arbor as shown at 13. Characters 10 are visible through a sight opening 14 in the face 7. The foregoing description relates to a well known construction of speedometer except for the stenciling of the numbers and to which my invention is applied.

The top wall of the casing 1 is provided with a light receiving opening 15 and located adjacent the opening is a stop plate 16 having one edge bevelled as shown in Figure 4 to be engaged by the bevelled edge of a light supporting plate 17 that overlies the opening 15 and carries an electric lamp socket 18 projecting into the casing. The plate 17 is provided with an offset portion 19 carrying an expandable socket 20 adapted to receive and grip the head 21 of a stub 22 carried by the top wall of the casing whereby the plate is detachably secured in place upon the casing.

40 An electric lamp 23 is mounted in the socket 18 and extends into the drum 9 and in rear of the stenciled numbers as clearly shown in Figures 2 and 4. The base of the lamp projects outwardly of the socket for engagement with a contact arm 24 carried by an insulating bracket 25 mounted on the plate 17 and is provided with a binding post 26 to receive the terminal of an electrical conductor. The plate 17 carries a binding post 27 to which the other electrical conductor of an electric circuit may be attached thereby illuminating the electric lamp 23.

45 A semi-transparent lining 28 is arranged within the drum 9 and overlies the stenciled

numbers for the purpose of profusing the rays of light from the lamp 23 so that undue glare will be prevented from the eyes of the observer. With the lamp 23 illuminated, the light rays shining through the semi-transparent lining 28 and the stenciled numbers will effectively illuminate the latter that they may be easily read.

The drum 9 below the stenciled numbers is provided with a plurality of slots 30 permitting the light rays from the lamp 23 to enter the interior of the casing for the purpose of providing an indirect lighting effect to the total and trip numbers 5 and 6 so that they may be easily read.

As shown in Figure 5, the drum 9 is operated through the driving mechanism 11 and equipped with the usual tension spring 31 for the purpose of returning the drum to zero marking when the speed of the vehicle is brought to a standstill. The dial 7 is preferably coated white, nickelized or tin plated on the inside to give it better reflecting qualities. When employing the device upon a motor vehicle, it is preferable to have the illuminating means employed on the dash extinguished so that the characters or numbers of the speedometer will be more easily read through the openings in the dial.

The outer face of the dial is preferably coated black.

While I have shown and described the preferred embodiment of my invention, it will be understood that minor changes in construction, combination and arrangement of parts may be made without departing from the spirit and scope of my invention, as claimed.

Having thus described my invention, what I claim is:

A speedometer comprising a casing having an opening, a speed indicating drum having stencilled characters mounted in the casing, a rim for said casing and provided with a cut-away portion adjacent the opening and having one wall thereof bevelled, a plate provided with a bevelled end engaging the bevelled wall of said cut-away portion and having the opposite end offset outwardly from the casing, a separable fastener between the offset end of the plate and said rim, a socket carried by said plate and extending into the casing by way of the opening and having the opposite end extending beyond the plate, an electric lamp carried by the socket and extending into the drum, an electrical terminal strip carried by the plate and insulated therefrom and engaging a terminal of the lamp, and an electrical terminal secured to said plate.

In testimony whereof I affix my signature.
CLAUDE M. PAXSON.
